DESIGN FOR A DRINK MUDDLER

Walter K. Youngberg, Middletown, Conn.

Application May 17, 1940, Serial No. 92,425

Term of patent 14 years

To all whom it may concern:

Be it known that I, Walter K. Youngberg, a citizen of the United States, residing at Middletown, in the county of Middlesex and State of Connecticut, have invented a certain new, original, and ornamental Design for Drink Muddlers, of which the following is a specification, reference being had to the accompanying drawing, forming part thereof.

In the drawing:

upper end of the drink muddler, a portion of the muddler stem being broken away to facilitate illustration, and

The dominant features of the design reside in the portions of the drink muddler shown in full lines.

I claim:

The ornamental design for a drink muddler, substantially as shown and described.

WALTER K. YOUNGBERG.
